US0D1016970S

(12) **United States Design Patent** (10) **Patent No.:** **US D1,016,970 S**
(45) **Date of Patent:** **** Mar. 5, 2024**

(54) **WATER FILTER**

(71) Applicant: **Qingdao Ecopure Filter Co., Ltd.**,
Qingdao (CN)

(72) Inventor: **Zhibin Zou**, Qingdao (CN)

(73) Assignee: **Qingdao Ecopure Filter Co., Ltd.**,
Qingdao (CN)

(**) Term: **15 Years**

(21) Appl. No.: **29/806,575**

(22) Filed: **Sep. 3, 2021**

(51) LOC (14) Cl. **23-01**

(52) U.S. Cl.

USPC **D23/209**

(58) **Field of Classification Search**

(57) **CLAIM**

I claim the ornamental design for a water filter, as shown and described.

DESCRIPTION

FIG. 1 is a front-right perspective view of a water filter according to the present application;

FIG. 2 is a front-top-right perspective view thereof;

FIG. 3 is a right-side view thereof;

FIG. 4 is a left-side view thereof;

FIG. 5 is a front-side view thereof;

FIG. 6 is a back-side view thereof;

FIG. 7 is a top view thereof, and,

FIG. 8 is a bottom view thereof.

The broken lines depict portions of the water filter that form no part of the claimed design.

1 Claim, 7 Drawing Sheets
